CHARLES DAY, OF GLASGOW, SCOTLAND.

JOINT AND JOINTING TOOL FOR TUBE WELLS.

Application filed October 4, 1924. Serial No. 741,672.

This invention comprises an improved joint for tube wells or the like in which two coaxial tubes of different diameters are joined below ground level, and also a jointing tool or plug useful in effecting a fluid-tight joint between the tubes.

In sinking a tube well, it is necessary to put down a sinking tube of sufficient internal diameter to permit free passage there-through of the strainer and the plain rising pipe attached thereto.

If, for any reason, it is desired to joint the strainer and rising pipe therefrom to a casing pipe, such joint having to be made below ground, and possibly under water, a specially constructed form of joint must be employed.

In modern tube wells it is usually requisite that the upper part of the well be of larger bore than the lower part, or strainer, generally because a pump has to be accommodated within the upper part.

Also, it is good practice to feed coarse sand or gravel down and around the strainer, while the sinking tube or outer casing pipe is being withdrawn.

Means should also be provided to prevent the sinking tube, outer casing or the like from parting company with the tube well or rising pipe from the strainer, when the former in withdrawal has reached the desired level on its return journey from the full depth of the bore.

I provide for leaving a portion of the sinking tube in the ground to form the casing of the pump.

In many deep wells it is found necessary to use a relatively large diameter of bore for the first few hundred feet and to reduce the diameter in steps as the bore proceeds. In wells of this description it is sometimes necessary to line the bore with tubing, and one object of this invention is to provide suitable means whereby the joints between the different lengths of different diameters may be made and also be kept fluid-tight.

As usually arranged, the joint formed will be a cement grouted joint, in which the cement does not take any tension or longitudinal stress tending to separate the two tubes, which stress, owing to the fact that it is sometimes advisable to suspend the strainer and pump casing at ground level, to prevent settlement of the tube well, is liable to be developed therein.

With the above and other objects in view the invention comprises a means for jointing below ground level two tubes of different diameters wherein the tube of larger diameter has, preferably at or near its lower end, an internally projecting part reducing the internal diameter thereof, said part having notches, slots, grooves or serrations on its interior surface. Said notches or the like extend only partly through said projecting part from the upper edge thereof, and the tube of smaller diameter has, preferably at or near its upper end, two or more, but preferably at least three, outwardly projecting lugs or the equivalent adapted to enter the notches or the like and to be engaged by the unbroken lower portion of the internally projecting part of the larger tube to form a joint therewith.

It will be understood that the internally projecting and the externally projecting parts on the tubes of larger and smaller diameter may be so positioned relatively to the ends of said tubes that when brought into engagement a joint having an overlap of desired amount may be formed between the two tubes.

The internally projecting part of the tube of larger diameter will usually be part of the cutting edge used for sinking said tube.

The annular space between the overlapping ends of the two tubes to be joined is filled with cement grout or the like, or with other suitable sealing material capable of setting solid after being deposited, for example asphalt or pitch, to complete the joint.

The invention also comprises a tool or plug to assist in forming the joint below ground, which plug is lowered into position and adapted to engage and seal off the top of the inner tube of smaller diameter and preferably also the outer tube of larger diameter above the annular space formed by the overlapping of the two tubes, and providing means whereby cement grout or other sealing material may be directed to fill the said annular space without entering the inner tube.

The plug comprises means for effecting fluid-tight contact with the interior surface of the pipe or space to be sealed, constituted by rings of rubber or other suitable material adapted to be expanded laterally and radially by pressure applied thereto by the tool

parallel to the axis of the tube well, whereby the necessary fluid-tight contact may be made.

The invention further comprises means for forming a fluid-tight joint to close off the lower end of the said annular space for grouting or sealing the same.

In the accompanying drawings Fig. 1 is a longitudinal section showing one embodiment of the joint with the plug in position for grouting the joint;

Fig. 2 is a cross-section on the line L—L of Fig. 1;

Fig. 3 is an elevation of the upper end of the rising pipe from the strainer or the upper end of the smaller and lower of the two pipes to be joined; and

Fig. 4 is a cross-section on the line X—X of Fig. 1.

1 is a projecting portion, which preferably may be the cutting shoe, the inner diameter of which is smaller than the inner diameter of the sinking tube or outer casing 2 which is to be jointed but larger than the outer diameter of the rising tube from the strainer or the lower section of the other tube 6 to be joined.

The interior surface of this projecting portion or cutting shoe 1 is grooved, notched or serrated as shown at 3, 3, the grooves or serrations increasing the diameter of the inner surface so that, at the bottom of said grooves, it is equal to the internal diameter of the casing 2. The grooves or serrations do not extend the full depth of this projecting portion from its top edge, so that the part 5 just above the inner bevel 4 of the cutting edge has its minimum internal diameter and at this point has an unbroken surface, not being reduced by the notches, serrations, grooves or the like.

A short distance below the top end of the rising tube 6 two or more, but preferably at least three, projecting lugs 8, 8, are riveted or otherwise connected to the rising tube. These lugs may conveniently take the shape of small pieces of angle iron. The outstanding legs of these lugs or the like are of such length that the lugs will act as centering means for centering the top of the inner or rising tube 6 and maintaining it substantially coaxial with the outer tube 2. That is to say, the outer diameter outside these lugs will be slightly less than the internal diameter of the casing 2, but distinctly greater than the internal diameter of the part 5. With this arrangement the two tubes 2 and 6 cannot part company, because if it is attempted to draw the outer tube, in withdrawing, when its cutting edge comes opposite the lugs 8 on the inner tube 6, the lugs will enter into some of the grooves or serrations 3 and will be engaged by the part 5. The outer tube 2 is thus adapted to engage the inner tube 6 in such a manner that

further withdrawal of the outer tube would cause the inner tube to rise with it.

Gravel or other suitable material may be fed down the annular space 9 between the two tubes during the process of withdrawal of the outer tube, so that in the final position the lower tube may be surrounded by a layer of gravel or the like separating this tube from the wall of the bore hole. In certain parts of the bore this space may be filled with an impervious material such as cement grout, the gravel or the like only being used in the neighbourhood of the strainer.

It will be seen that a strong joint, capable of resisting tensile forces, is effected, space is left for feeding down gravel, and the serrations inside the cutting shoe permit any lengths of pipe which may have been screwed to the top of the tube well to be unscrewed without rotating the sinking tube.

To stop the entry of sand which might rise up between the overlap of the two tubes, I fill the space between them with Portland cement grout, the grout acting as a filler only.

Or I may use lead shot or any other filler.

In filling the annular space provision is made for blocking the flow of grout both upwards and downwards, and confining it as far as possible to the annular space between the overlapping parts of the pipes.

An annular rubber packing 10 may be inserted from above and caused to take up a position resting on top of the lugs 8, 8 in the annular space between the overlapping parts of the pipes 2 and 6. If preferred, this rubber packing ring may be fitted or fixed to the pipe 6, or to either pipe, in its desired position before the pipe is lowered in position.

Preferably a metal ring or washer 11 giving suitable clearances is first placed upon the tops of the lugs 8 so as to give sufficient support to the rubber packing 10.

For blocking the annular space on top there is used a tool or plug comprising a central part 12 which is mounted on a central hollow shaft 13 so that it can freely rotate on the latter. An upper sleeve 14 and a lower sleeve 15 are also mounted on the shaft 13, engaging, respectively, a right-handed and a left-handed screw-thread 16 and 17 on the exterior of the shaft 13. Means such as studs 18 or pins 19 may be provided which enter sockets in the part 12, preventing the two sleeves 14 and 15 from rotating relatively to the part 12. A cup 20 holds the parts together. Rubber ring or other suitable packings 21 are inserted in a depression or gland 22 between the parts 12 and 14, these rings being adapted upon compression to expand laterally and radially and to form a fluid-tight contact between the plug and the inner surface of the tube 2. Other rubber rings 23 inserted in a depres-

sion or gland space 24 between the parts 12 and 15 are adapted upon compression to expand laterally and radially and to form a fluid-tight contact between the plug and the inner surface of the tubes 6.

The upper edge of the inner tube 6 is provided with slots 25 adapted to be engaged by projections or pins 26 fixed to the part 12. The parts 15 and 20 of the plug may be coned ¹⁰ to permit the plug to enter freely the upper part of the tube 6.

The plug is fixed to a hollow down pipe by which the tube 13 may be rotated and through which cement grout may be poured.

¹⁵ An eye-bolt 28 is suspended by a wire or the like 29 inside the bottom of the hollow tube 13. On this bolt are strung rubber washers 30 which may be expanded laterally and radially by tightening up the nut 31 to ²⁰ engage the interior of the hollow shaft 13 and form a fluid-tight joint therewith.

The hollow shaft 13 has perforations 32 for grout or the like to pass through and to find its way through passages 33 to the annular space 34 between the overlapping portions of the two tubes 2 and 6 to be joined.

The stopper constituted by the washers 30 is of such length that when resting on the edge of the cup 20 its upper end does not ³⁰ cover the holes 32 in the tube 13.

A spring 35 attached to the stopper 30 may pass through a hole 36 in the cup 20 and the shape and length of this spring and the hole in the cap may be so arranged that if the ³⁵ stopper 30 is drawn up by pulling on the cord 29 this spring will be drawn through the hole and will spring outwards and engage the interior upper surface of the cup when the stopper 30 is sealing off the holes ⁴⁰ 32.

In action, the two tubes 2 and 6 being in their desired relative positions and the washer 10 being in position, the plug is lowered until it enters the top of the tube 6.

⁴⁵ It is then slightly rotated until the pins or the like 26 drop into the slots 25 in the top of the tube 6 which will prevent further rotation of the central part 12 of the plug relatively to the tube 6. This action also

prevents rotation of the parts 14 and 15. ⁵⁰ The shaft 13 is then rotated further to cause the two parts 14 and 15 to approach each other. This action may be due to the right and left handed threads on the said parts and the corresponding threads 16 and 17 on ⁵⁵ the shaft 13. Or, if preferred, one part, preferably the upper 14, may merely be compressed against a collar 37 by the movement of the other part towards it. In either case the action is such that the rubber rings 21 ⁶⁰ and 23 are expanded to make fluid-tight joints with the two tubes 2 and 6 and to isolate the annular space to receive grout.

Grout is now poured in to fill this space and the rubber stopper 30 may then be partly ⁶⁵ withdrawn to close off the perforations 32 and to prevent any leakage of grout as the tool is being withdrawn.

What I claim is:—

In a well tube, a molded joint comprising two co-axial tubes of different diameters entering one within the other with the lower end of the outer tube overlapping the upper end of the inner tube of less diameter, leaving between the overlapping ends an annular space, an annulus fixed to the exterior of and extending below the lower end of said outer tube, the extension of said annulus being formed with a contracted zone of an internal diameter less than the internal diameter of said outer tube, the inner face of said annulus being provided above the part of maximum contraction with longitudinal ⁷⁰ ⁷⁵ ⁸⁰ ⁸⁵ grooves, lugs fixed to the exterior of said inner tube above said zone of maximum contraction and adapted to enter grooves in said annulus, the outer surface of said lugs being situated on the circumference of a circle of less diameter than the internal diameter of said outer tube but of greater diameter ⁹⁰ than said part of maximum contraction, and packing resting on said lugs and serving to close the lower end of said annular space, the upper end of said annular space being open to receive sealing medium. ⁹⁵

In testimony whereof I have signed my name to this specification.

CHARLES DAY.
